UNITED STATES PATENT OFFICE.

EDMUND R. BARANY AND LEON B. MANSON, OF NEW YORK, N. Y., ASSIGNEES TO
FRANCO ELECTRIC CORPORATION, A CORPORATION OF NEW YORK.

FLASH LIGHT.

Application filed September 14, 1921. Serial No. 500,508.

To all whom it may concern:

Be it known that we, EDMUND R. BARANY, a citizen of the United States, and LEON B. MANSON, a citizen of Russia, residents respectively of the city, county, and State of New York, have invented certain new and useful Improvements in Flash Lights, of which the following is a specification.

This invention relates to portable electric 10 lamps of the class commonly known as flash-lights.

Flashlights of the types most widely exploited today depend entirely upon a single bulb as a source of light which may and often 15 does burn out at the instant a light is most needed, thus leaving the user of the flashlight suddenly in darkness without any reserve or auxiliary light to be had, under what may prove to be very annoying or even 20 hazardous circumstances.

Devices of this character are therefore very unreliable and for this reason are open to serious objections, the removal of which constitutes one of the important objects of 25 our invention.

Another object of our invention is to provide in a flashlight a means by which a primary lamp and one or more auxiliary lamps may be so mounted and supported with respect to the reflector as to permit the light 30 rays to be projected upon the reflector in an unobstructed manner.

A further object of our invention is to provide in a device of the class mentioned a 35 means whereby a single switch actuating mechanism may be employed to control one or more of the several circuits connecting the plurality of lamps with the source of electric supply.

A still further object is to so construct and arrange the various elements entering into the combination embodying our invention as to provide a neat, compact and durable device, the advantages of which will 45 become apparent from the following specification taken in connection with the accompanying drawings, in which—

Figure 1 is a view in elevation showing an assembled flashlight embodying our invention.

Figure 2 is a central longitudinal sectional view taken on line 2—2 of Figure 1.

Figure 3 is a view similar to that of Figure 1, certain portions of the device being 55 shown in section.

Figure 4 is a transverse sectional view taken on line 4—4 of Figure 3.

Figure 5 is a transverse sectional view taken on line 5—5 of Figure 1.

Figure 6 is a plan view of a multiple 60 switch element.

Figure 7 is a diagrammatic view illustrating the circuits through which the plurality of lamps receive their supply of electric current.

In the drawings, wherein for the purpose of illustration is shown what we at present consider the preferred embodiment of our invention, the numeral 10 indicates a casing or container, constructed preferably of fibre 70 or other suitable insulating material, carrying therein a source of electric supply which we have in this instance shown as a single battery 11 of ordinary construction, in which the lowermost zinc container 12 thereof constitutes an electrode adapted to be placed in circuit with the uppermost carbon electrode 13 and a plurality of lamps hereinafter more specifically referred to. While we prefer, as above stated, to construct the casing or 75 container of fibre or other suitable insulating material, in order to insulate from each other the several elements hereinafter referred to, which constitute the circuit through which the current passes when the lamps are placed in circuit with the battery 11, it will appear from the drawings that these 80 elements may be otherwise insulated to permit the use of a metal casing if desired, without departing from the spirit of the invention.

The casing or container 10 carries at one end thereof a reflector receiving head 14 having at its enlarged end screw threads adapted for screw thread engagement with a lens ring 15, which serves to maintain a lens or a glass closure 16 in position and in intimate contact with the outer end of a reflector 17, which is seated upon the end of the casing or container 10. By reason of the 85 fact that the reflector 17 is seated directly upon the casing or container 10, it is evident that the same is necessarily maintained centrally located with respect to the container 10 when the lens or glass plate 16 is forced into contact with the outer end of the reflector 17 by the lens ring 15. It will be 90 noted that the reflector receiving head 14 and the reflector 17 are at their outer ends spaced a sufficient distance from each other to insure perfect insulation therebetween,

100 105 110

and the reflector receiving head 14 is increasingly spaced rearwardly from the reflector 17 due to the different radii of curvature maintained between these two elements 5 in order to provide a bulb space 18.

The reflector 17 which may be termed a primary reflector is provided with oppositely disposed openings 19 within which are fitted auxiliary reflectors 20 tapered 10 rearwardly and terminating in bulb receiving sockets 21 adapted to receive auxiliary lamps 22. The reflectors 20 serve not only as reflectors for the auxiliary lamps 22, but also as supports therefor, and are so shaped 15 as to accommodate the lamp bulbs 23 which are preferably somewhat flattened as shown in order that the greater portions thereof may be positioned rearwardly with respect to the reflector 17 and out of the curvature 20 of the same.

As a primary source of light we provide a primary lamp 24, the bulb 25 of which projects an appreciable distance forwardly with respect to the reflector 17 and is so 25 disposed as to lie within the curvature of the same. The lamp 24 is supported in position by means of a support 26 preferably formed integral with the reflector 17 and depends primarily upon the reflector 17 as 30 a means for reflecting the light rays which are given off thereby, whereas the lamps 23 depend to a less degree upon the reflector 17 for reflecting the light rays emitted thereby. It will be appreciated, however, that 35 the reflectors 20, serving also as supports for the lamps 23 as hereinbefore mentioned, function co-operatively with the reflector 17 for reflecting the light rays given off by the lamps 23, and inasmuch as the greater 40 portions of the lamps 22 are disposed out of the curvature of the reflector 17, it will be appreciated that light rays are permitted to pass from the lamp 24 to the reflector 17 in an unobstructed manner.

45 In order to accommodate the reflectors 20 and the lamps 22 carried thereby, it becomes necessary to provide relatively large notches 27 at that end of the container 10 upon which the reflector 17 is supported. In assembling the flashlight embodying our invention, the reflector 17 is so inserted that the auxiliary reflectors 20 enter the notches 27, and being thus positioned any relative turning movement of the reflector with respect to the container is prevented when the closure 16 and lens ring 15 are applied.

The battery 11 is electrically connected with the reflector 17 by means of a contact strip 28 suitably secured to the container 10 and having one of its ends bent slightly over the edge of the container, as shown at 29, so as to intimately contact with the reflector 17 when the same is assembled in a proper relation with respect to the 60 container 10. The opposite end of the con-

tact strip 28 is bent to provide a contact arm 30, which is more or less resilient and maintained in intimate engagement with the carbon electrode 13 by reason of the longitudinal thrust constantly exerted upon the battery 11 by means of the conventional type of spring 31 carried at the opposite end of the battery and held in position by means of a screw threaded closure 32 carried by the container 10, but adapted to be removed 70 therefrom to permit the removal of the battery 11 in order that the same may be replaced with a new one when desired.

It will be understood that the lamps 22 and 24 above referred to are of ordinary 80 construction and that by reason of either their direct or indirect connection with the reflector 17, they are therefore electrically connected with the carbon electrode 13 through the reflector and the contact strip 28. The lamps 22 and 24 are each co-operatively associated with conductors 33 and 34 leading respectively therefrom. The conductors 33 it will be noted are oppositely or diametrically disposed and are arranged adjacent the openings 27 so that, when the reflector 17 is properly positioned with respect to the container 10, a positive contact between the lamps 22 and the conductors 33 is insured. The conductors 33 are bent into 90 an angular shape and are connected to conductors 35 which are suitably secured to the container 10. The conductor 34 leading from the primary lamp 24 is at its upper end disposed substantially in a plane transverse to the axis of the container 10 and is bent to provide a relatively long conductor strip 36 which is suitably secured to the container 10 by means of rivets or the like 37 and 38, the rivet 38 serving as a 100 contact point as will hereinafter appear. The conductors 35 are connected to conductor strips 39 which are secured to the container 10 by means of rivets 40 and 42, the rivets 42 serving also as contact points, the 110 function of which will hereinafter more clearly appear.

In order to place the conductor strips 36 and 39 in circuit with the battery 11 to establish a circuit through the lamps 22 and 24, we provide a switch indicated as a whole by the numeral 43. The switch 43 comprises a contact element 44 constructed from a more or less resilient material and provided with contact arms 45 and 46 carrying respectively lugs 47 and 48. The contact element 44, which is rigidly connected to the container 10, is electrically connected with the battery 11 by means of a conductor strip 49, one end of which is maintained in contact with the screw cap 32, whereas the other end is connected to the contact element 44 by means of a rivet or the like 50. The ends of the contact arms 45 and 46 are disposed opposite the contact points 38 and 42 of the 120 130

conductor strips 36 and 39 respectively, and are normally spaced an appreciable distance from said contact points as clearly shown in Figures 2 and 5. A housing 51 is provided 5 which encloses the contact element 44 in order to protect the same and insure the contact fingers 45 and 46 against being accidentally moved into contact with their respective co-operative contact points 38 and 42. In order to move the contact fingers 45 and 46 into contact respectively with the contact points 38 and 42, we provide a switch actuating member 52, of usual construction, which is free to slide upon the housing 51 10 into contact with and over the lugs 47 and 48 carried respectively by the fingers 45 and 46, which lugs project upwardly through the housing 51. From an inspection of the circuit employed in connection with our invention, it will appear that the circuit through 15 the primary lamp 24 may be closed by moving the switch actuating member 52 over the lug 47 in order that the arm may be depressed into contact with the contact point 38, and that by further moving the switch actuating member 52 the circuits through the primary lamps 23 may be closed by similarly depressing the contact arms 46 into engagement with the contact points 42. 20 From a study of the drawings it will appear that either one or all of the lamps may be placed in circuit with the battery 11 by proper manipulation of the switch actuating member 52. In the event that a light of ordinary brilliancy is desired, the switch actuating member 52 is moved a sufficient distance to close the circuit through the primary lamp 24 by placing the contact finger 45 in electric engagement with the contact 25 point 38, but in the event a more brilliant light should be desired, the switch actuating member 52 may be moved a sufficient distance to close the circuit through one or both of the auxiliary lamps 22 by depressing either one or both of the contact arms 46 30 into electrical engagement with either one or both of the contact points 42. From the construction which we have disclosed it is evident that should the primary bulb 25 suddenly burn out, leaving the user of the flashlight temporarily in the dark, the circuit may be readily closed through either or both of the auxiliary lamps 22, in order to furnish a light sufficiently brilliant for all practical purposes. Not only does the construction which we have disclosed afford a means by which an auxiliary light may be had almost instantly in case the primary lamp 24 should burn out, but also a means by which 35 a combination of different colored lights may be employed for various signaling purposes. Should a combination such for example as white, red and blue be desired, the lamps 22, which for ordinary use are provided with clear glass bulbs, are removed

from their sockets 21 to permit the insertion of lamps having red and blue bulbs, the lamp 24 being retained with its clear glass bulb 25 as a source of white light. It may be appreciated therefore that should it be 40 desired to transmit a signal by a white light the switch actuating mechanism 52 may be moved a sufficient distance to depress the contact arm 45 into engagement with the contact point 38, thereby closing the circuit 45 through this particular lamp and the battery 11, and should it be desired to display a red and blue light in combination with the white light, the switch actuating member 52 may be moved a sufficient distance to depress the contact arms 46 into engagement with their respective contact points 42, thereby placing the battery 11 in circuit with the lamps having the red and blue bulbs. 50

While we have shown a switch actuating mechanism adapted to co-operate with the contact arms to close the circuit through the lamps, it is evident that, since the lugs 47 and 48 project an appreciable distance 55 through the housings 51, the user of the flashlight may with his thumb or fingers selectively depress the contact arms 45 and 46 to establish a circuit through any one or any combination of the lamps desired, thereby 60 making possible the transmission of a greater number of signals than is possible when the switch actuating mechanism is depended upon as a means for closing the circuits through the lamps. By reason of the fact that the contact arms 45 and 46 are spaced an appreciable distance from each other and the lugs 47 and 48 carried respectively thereby are projected through the 65 housings 51 in a staggered relation with respect to each other, the user of the flashlight may easily locate a switch arm adapted to close the circuit through a selected lamp or any number of switch arms to close the circuits through any desired combination of 70 the lamps. 75

We have not attempted to point out the many specific uses to which a flashlight embodying our invention may be put, but it may be appreciated that it is capable of a 80 varied range of application because of its adaptability as a signal and because of its reliability as a flashlight, and it may be further appreciated from a study of the drawings that various changes in the size, 85 shape and arrangement of parts, in what we have shown and described as the preferred embodiment of our device, may be made without departing from the spirit of the invention or the scope of the subjoining claims. 90

We claim:

1. A flashlight comprising a container, a reflector receiving head, a reflector arranged within said head and seated upon one end of said container, said reflector being spaced at 95

- 4
- its forward end an appreciable distance from said head and increasingly spaced rearwardly therefrom, and means for retaining said reflector seated upon said container and centrally disposed with respect to the axis of said head whereby the spaced relation between the head and reflector is maintained to insure insulation of said head from said reflector.
- 10 2. A flashlight comprising a battery, a plurality of lamps adapted to be placed in circuit with said battery, a switch for controlling the circuits through said lamps, said switch comprising a plurality of contact arms, lugs carried by said contact arms, said lugs being staggered with respect to each other, a housing for said contact arms, said housing being provided with openings through which said lugs project, and a switch actuating member adapted to co-operate with each of said lugs for depressing said contact arms into circuit-closing positions.
- 15 3. A flashlight comprising a container having notches therein at one end of the same, a reflector receiving head, a reflector arranged within said head, a plurality of lamp supports secured to said reflector and projecting rearwardly therefrom, said supports being arranged within said notches formed in said container, whereby said reflector is retained against rotative movement with respect to the container, lamps carried by said lamp supports, a source of electrical energy for said lamps, and means for electrically connecting said lamps in circuit with said source of energy.
- 20 4. A flashlight comprising a battery, a plurality of lamps adapted to be placed in circuit with said battery, a switch for controlling the circuits through said lamps, said switch comprising a plurality of arms adapted to be electrically connected in circuit with said lamps, and a movable switch actuating means adapted to be so moved as to maintain all of said arms in circuit closing positions at the same time.
- 25 5. A flashlight comprising a battery, a plurality of lamps adapted to be placed in circuit with said battery, a switch for controlling the circuits through said lamps, said switch comprising a plurality of arms adapted to be electrically connected in circuit with said lamps, and a movable switch actuating member adapted to be so moved as to maintain all of said arms in circuit closing positions at the same time.
- 30 6. A flashlight comprising a battery, a plurality of lamps adapted to be placed in circuit with said battery, a switch for controlling the circuits through said lamps, said switch comprising a plurality of arms adapted to be electrically connected in circuit with said lamps, and a movable switch actuating member adapted to be so actuated as to progressively move said arms into circuit closing positions and thereafter maintain them in their respective circuit closing positions.
- 35 7. A flashlight comprising a container adapted to receive a source of electrical energy, said container being provided at one end thereof with diametrically disposed notches, a reflector head associated with said container, a primary reflector arranged within said head and adapted to seat upon said container, a plurality of auxiliary reflectors carried by said primary reflector, said auxiliary reflectors terminating in rearwardly projecting lamp sockets adapted to enter said diametrically disposed notches whereby said primary reflector is retained against rotation with respect to said container, electric lamps carried by said lamp sockets, and means for placing said lamps in electric circuit with said source of electrical energy.
- 40 8. A flashlight comprising a container adapted to receive a source of electrical energy, a reflector, a plurality of lamps associated with said reflector, conductor strips leading individually to said lamps, said conductor strips being carried by said container, movable contact members adapted to cooperate with said conductor strips for closing the circuit through said lamps, means electrically connecting said contact members with said source of electrical energy, and means adapted to so cooperate with said contact members as to move them progressively into cooperative relation with said conductor strips and thereafter retain them in their respective positions.
- 45 9. A flashlight comprising a container adapted to receive a source of electrical energy, a reflector, a plurality of lamps associated with said reflector, conductors leading to said lamps, a switch adapted to control the flow of current through said lamps, said switch comprising a contact element struck out to provide a plurality of contact arms, and movable means adapted to be so actuated as to establish electrical connection between said conductors and said arms to close the circuit through said lamps.
- 50 10. A flashlight comprising a container adapted to receive a source of electrical energy, a reflector, a plurality of lamps associated with said reflector, conductors leading to said lamps, a switch adapted to control the flow of current through said lamps, said switch comprising a contact element having a plurality of resilient contact arms associated therewith, and movable means adapted to so actuate as to progressively move said resilient arms whereby the circuits through said lamps are successively closed.
- 55 In testimony whereof, we have affixed our signatures to this specification.
- EDMUND R. BARANY.
LEON B. MANSON.
